United States Patent Office

Des. 187,044
Patented Jan. 12, 1960

187,044

PIN OR SIMILAR ARTICLE

Anton Kun, New York, N.Y.

Application June 22, 1959, Serial No. 56,480

Term of patent 3½ years

(Cl. D45—19)

FIG. 1.

FIG. 2.

Fig. 1 is a front elevational view of a pin or similar article embodying my design; and

Fig. 2 is a side elevational view thereof.

The essential features of my design reside in the portion shown in full lines.

I claim:

The ornamental design for a pin or similar article, as shown and described.
